UNITED STATES PATENT OFFICE.

JAMES G. McCONNELL, OF CHICAGO, ILLINOIS.

MAP HEAD.

Application filed August 7, 1924. Serial No. 730,699.

This invention relates to map heads or binders for supporting maps and provides means whereby the maps may be either hung up or mounted on a stand or rolled around the head as for shipping or storage purposes. The present invention provides means whereby a number of maps may be supported on one head or cross piece and the tops or edges where the maps are supported may be firmly pressed or bound together in order to support the maps without tearing. My improved head or binding device also provides means for protecting or stiffening the maps when they are rolled upon the same and means whereby the maps may be readily adjusted for exposing different maps in the series. Other objects of this invention are to provide a map head made of few parts but which will be readily adjustable for different numbers of maps or other sheets; to provide a simple and efficient binding and supporting member for maps, sheets or the like; and, in general, to provide such an improved device as will be more fully described hereinafter.

In the accompanying drawings illustrating this invention;

Figure 1 is a front view showing the device in hanging position;

Figure 2 is an enlarged sectional view taken on the line 2—2 of Figure 1;

Figure 3 is an enlarged sectional view taken on the line 3—3 of Figure 1 and showing the head in reversed position for supporting maps on the stand; and

Figure 4 is an enlarged front view showing the hanger in closed position.

In the particular form of my invention as shown in these drawings the head comprises two main strips or supporting members 5 and 6 which are preferably made of sheet metal such as steel or the like. The strip or bar 5 is provided with curved flanges or rolled edges 7 and 8. These flanges are disposed on opposite sides of the strip so that the strip is S-shaped in cross section. The plate or strip 6 is provided with a rolled edge or flange 9 at one edge thereof and is oppositely disposed to the flange 8. The binding edges of the articles to be supported such as sheets or maps 10 are positioned between the strips 5 and 6 as shown particularly in Figure 2 and bolts 11 extend through the strips and sheets to hold the parts together. When the nuts 12 are tightened the edges of the maps will be held together and in position by fric-

tion so that they are not apt to become torn and they are further protected by the rolled edge 7 which makes a back for the binding pieces. Such flanged strips or plates are very stiff in proportion to their weight and provide a substantial roller or stiffening member around which the maps may be rolled and the curved edges prevent the maps from being creased or bent when rolled around the head. The head is provided with clips or hangers 13 for supporting the maps when they are to be hung on the wall. These clips have holes for receiving the bolts 11 and are held by nuts 14. Their opposite ends are provided with holes 15 for engagement with screws, nails or the like on the wall. When the maps are to be rolled on the head, these clips may be swung to folded position as shown in Figure 4.

The plate or strip 5 is provided with a socket 16 for receiving the rod or supporting stem as indicated in dotted lines 17. When the head is supported in this position, the rolled edges 8 and 9 are at the top and the maps or leaves may be folded from one side to the other as illustrated in Figure 3 and will be supported over these rolled edges so that they are not apt to be creased or broken. My improved head provides means whereby it may be adjusted for different numbers of maps or leaves and when so adjusted it will hold such maps or leaves securely together. The head or supporting device may be made in various sizes and may be modified for different conditions and therefore I do not wish to be limited to the exact arrangement herein shown and described, except as pointed out in the following claims, in which I claim:

1. A map head comprising a rigid strip having oppositely disposed rolled edges, a second rigid strip having one rolled edge and means for fastening the strips together to hold the sheets therebetween.

2. A map head comprising a metallic strip of substantially S-shape in cross section, a second strip of substantially the same width as the first strip and having a rolled edge along one side thereof and bolts for fastening the strips together and clamping maps or the like between the same.

3. A map head comprising two stiff strips having longitudinal flanges, bolts for fastening the strips together and hangers engaging with said bolts.

4. A map head comprising two strips hav-

ing longitudinal flanges, a socket on one of said strips for receiving a supporting rod and means for fastening the strips together.

5. The combination with one or more maps or sheets, of a pair of metallic binding strips having oppositely disposed curved flanges for stiffening the same, and over which the maps may be folded, bolts extending through said strips and maps, and clips 10 engaging with said bolts.

6. The combination with a plurality of maps, of a binding strip having oppositely disposed rolled edges, one of said rolled edges projecting over the binding edges of 15 the maps, a second strip having a rolled edge arranged oppositely to the lower rolled edge

of the first named strip, bolts passing through said strips at the edges of the maps and means for supporting said head.

7. A map head comprising a sheet metal 20 plate having upper and lower curved flanges, a second strip having a curved flange disposed oppositely to the lower curved flange of the first named strip and bolts or the like passing through said strips for pressing 25 them against the maps, the arrangement being such that the maps may be rolled around said curved flanges without being readily creased or broken, substantially as described.

JAMES G. McCONNELL.
